CLAIM

The ornamental design for desk-top/wall-mount charger base, as shown and described.

DESCRIPTION

FIG. 1 is a perspective view of desk-top/wall-mount charger base showing the top, front and right side, shown with a phantom line phone in desk-top orientation;

FIG. 2 is a front plan view of our new design;

FIG. 3 is a right side elevation view of our new design;

FIG. 4 is a bottom plan view of our new design;

FIG. 5 is a top plan view of our new design;

FIG. 6 is a section taken along cut-line 6—6 in FIG. 5;

FIG. 7 is a rear elevation view;

FIG. 8 is a section taken along cut-line 8—8 in FIG. 5;

FIG. 9 is a left side elevation of our new design; and,

FIG. 10 is a perspective view of the rear, top and right side,

shown with a phantom line phone in wall-mount orientation. The phantom line showing throughout the drawing figures is included for the purpose of illustrating environmental structure only and forms no part of the claimed design.
